UNITED STATES PATENT OFFICE.

CORNELIUS P. HOUTSMA, OF OCHEYEDAN, IOWA.

GRAIN BINDER.

Application filed January 7, 1926. Serial No. 79,777.

It is the object of my invention to provide a grain binder of simple, durable and comparatively inexpensive construction.

More particularly it is my object to provide a grain binder having one main shaft for driving all the binder mechanism therefrom.

A further object is to provide means for connecting a motor or a tractor for furnishing the motive power for the binder mechanism.

Still a further object is to provide an improved means for driving the sickle.

With these and other objects in view, my invention consists in the construction, arrangement and combination of the various parts of my binder, whereby the objects contemplated are attained, as hereinafter more fully set forth, pointed out in my claims, and illustrated in the accompanying drawings, in which:

Figure 1, is a front elevation of a portion of a grain binder embodying my invention.

Figure 2, is a plan view of the same taken on line 2—2 of Figure 1.

Figure 3, is a side elevation of the same taken on line 3—3 of Figure 2.

Figures 4 and 5 are enlarged detail sectional views taken on lines 4—4 and 5—5 of Figure 1.

Figure 6, is an enlarged detail sectional view taken on line 6—6 of Figure 2.

In the accompanying drawings I have used the reference numeral 10 to indicate the sickle of a grain binder of the usual construction.

Other parts used in such a binder are the platform conveyor 11 and elevating conveyor 12 shown in dashed lines in Figure 1.

A float conveyor 13 is also found in the usual binder and is shown in dashed lines in

Figure 1.

A conveyor 14 supports the conveyors 12 and 13. The elevating conveyor 12 operates the floating conveyor through a chain of gears 13^a. A bevel gear 12^a operates the reel operating shaft 12^b.

A binder deck 15 is supported by brackets 15^a on a sliding angle 16 and by the binder crane 17. Rotatively supported from the binder deck 15 in brackets 18, is a packer shaft 19.

A bull wheel 20 is supported in guides 21 and by means of a worm gear mechanism 22, is adjustable in the guides 21.

All the foregoing is of the usual binder construction and forms no part of my invention.

For supporting the conveyor frame 14 and the platform conveyor 11, I have provided a frame consisting of longitudinal members 23 to which the guides 21 are secured.

Secured to the frame members 23 is a front looped member 24 and rear frame members 25 and 26.

On the frame member 24 is a bracket 27. The conveyor frame 14 is secured at its upper end to the bracket 27 and to the end 28 of the frame member 25.

The lower end of the conveyor frame 14 is connected to the bracket 29 attached to the frame members 23 and extending laterally 70 therefrom. For bracing the member 29, I provide a brace 29^a secured to one of the frame members 23 and the front frame member 24.

The forward end of the brace 29^a has an opening 29^b to receive the tongue or tongue truck which is part of the ordinary binder and not shown on the drawings.

The frame 14 is also connected to the lateral extension 30 of the frame member 26.

The platform conveyor 11 has a frame 31 80 which is secured to the extensions 29 and 30.

Brackets 32 are secured to the frame members 24 and 25 for slidably supporting the angle 16.

A bracket 33 supports the binder crane 17. 85 The bracket is braced by a brace 70 secured thereto and extending to the guide 21. Thus it will be seen that I have provided a frame which supports the elements of the usual binder.

For driving the binder mechanism I provide a driving shaft 34 mounted in bearings 35, which are preferably of the self aligning roller bearing type and are secured to the frame members 23 and 24.

The usual binder has a clutch 36 operated by a lever 37 and this clutch 36, I mount on the shaft 34.

A chain 38, connects a sprocket 39 on the bull wheel 20 to a sprocket 41 on the driving 100 shaft 34.

The clutch 36 is designed to operatively connect the sprocket 39 to the shaft 34 whereby rotation of the bull wheel 20 will cause the drive shaft 34 to rotate.

For driving the sickle 10, I provide a shaft

42 mounted in bearings 43, preferably of the self aligning roller bearing type, on the bracket 33.

Bevel gears 44 and 45 transmit motion from the drive shaft 34 to the sickle shaft 42. On the sickle shaft 42 is a disk 43 having the crank pin 46 secured thereto.

A pitman 47 is mounted on the pin 46 with a bushing 48 interposed between the pitman 10 and the pin. The pitman 47 is pivotally secured at 49 to the sickle bar 50 which is slidably mounted in the slide 51.

The slide 51 is supported on the lateral extending member 29.

For driving the platform and elevating conveyors, I provide a shaft 52 mounted in self aligning roller bearings 53.

A bevel gear 54 thereon meshes with a bevel gear 55 on the drive shaft 34.

A sprocket 56 is connected by a chain 57 to the sprocket 58 on the elevating conveyor and to the sprocket 59 on the platform conveyor.

The ends 60 and 60^a of the shaft 52 are square. The purpose of this is so that if it is desired to mount a motor on the binder frame, the motor can be connected to the end 60 for operating the binder mechanism.

If a tractor is employed in pulling the binder, it can be operatively connected to the end 60^a for accomplishing the same result.

The bevel gear 44 on the shaft 34 has a wheel portion 61 having flat blades 62. The blades 62 coat with rollers 63 on a wheel 64 which is secured to a sleeve 65 by means of cap screws 66.

The sleeve 65 is rotatively mounted in a bearing 67 and has a square opening through its center for receiving a squared portion 68 of the packer shaft 19. The bearing 67 has a portion 67^a illustrated in Figure 6, which is bolted to one of the upper frame members 23 by means of a bolt 67^b through a slot 67^c in the portion 67^a. This arrangement permits adjustment of the bearing 67 longitudinally of the packer shaft 19 for disengaging the wheel 64 from the wheel 61 for the purpose of operating the binder mechanism on the deck 15 by hand when adjusting or repairing any part of said mechanism.

Thus it will be seen that rotation of the drive shaft 34 is transmitted through the wheels 61 and 64 to the packer shaft for operating the packer mechanism.

The end 69 of the shaft 68 extends over to the bundle tying mechanism which forms part of the binding mechanism and is mounted on the disk 15 but is not shown on the drawings as it is part of the usual binder construction.

The purpose of constructing the wheel 64 and the bushing 65 as shown, is so that when the platform 15 is slid endwise by sliding the angle 16, the shaft 68 slides through the bush-

ing 65 at all times maintaining an operative connection therewith.

By mounting the wheel 64 as shown it can be reversed on the bushing 65 so that the rollers 63 are on the opposite side of the hub 64^a for the purpose of adapting my device to binders of other makes.

Thus it will be seen that I have provided a construction which has one drive shaft from which all parts of the binder mechanism will be driven. In this way this driving is not done from the sickle shaft as is the case in the binder in use today.

By providing a frame as I have in my invention, I eliminate the necessity of a cross-brace just rearwardly of the pitman 47. This enables me to position the bull wheel 20^a farther ahead than is possible in a grain binder having a frame of the usual type. By thus positioning the bull wheel the weight of the binder is nearer balanced thereon and less weight is thrown on the tongue truck thereby giving better traction which is especially desirable when harvesting in wet fields.

Some changes may be made in the construction and arrangement of the various parts of my invention, without departing from the real spirit and purpose of my invention; and it is my intention to cover by my claims, any modified forms of structure or use of mechanical equivalents, which may be reasonably included within their scope.

I claim as my invention:

1. In a device of the class described, a wheel mounted frame, a drive shaft journaled thereon parallel to and positioned above the axis of the wheel, a vertical sickle operating shaft operatively connected to said drive shaft, a packer shaft at right angles to said drive shaft and means for operatively connecting said packer shaft to said drive shaft, said means comprising a pair of wheels operatively engaging each other, a sleeve rotatably mounted and operatively connected to said packer shaft, one of said wheels having a hub offset relative to the periphery thereof and secured to said sleeve.

2. In a device of the class described, a wheel mounted frame, a main drive shaft journaled thereon parallel to and positioned above the axis of the wheel, a vertical sickle operating shaft operatively connected to said drive shaft, a packer shaft at right angles to said drive shaft and means for operatively connecting said packer shaft to said drive shaft, a conveyor shaft parallel to said packer shaft and operatively connected to said drive shaft and having free ends adapted for the connection of motor power to either end of said conveyor shaft.

3. A binder comprising a frame, a bull wheel mounted therein, a drive shaft mounted parallel to and positioned above the axis of said bull wheel, a conveyor operating shaft

mounted at right angles to said drive shaft and operatively connected thereto, a vertical sickle operating shaft operatively connected to said drive shaft, a packer shaft driving 5 means comprising a bracket, a sleeve journaled therein, a wheel having radially extending rollers on its periphery and having a hub secured to said sleeve, a paddle wheel secured to said drive shaft and cooperating 10 with said rollers and a packer shaft slidably mounted through said sleeve.

4. A binder comprising a frame for supporting the conveyors, sickle and binder deck 15 of a binder, a bull wheel mounted therein, a drive shaft mounted parallel to and above the axis of said bull wheel, a packer shaft and a conveyor operating shaft mounted at right angles to said drive shaft, the axis line of

said packer shaft and said drive shaft intersecting each other, a flat bladed wheel 20 mounted on said drive shaft, a wheel having rollers extending radially therefrom rotatably mounted on said frame in position where said rollers will coat with said flat bladed wheel, said packer shaft being slidably 25 mounted through said wheel having rollers, bevel gears connecting said conveyor operating shaft to said drive shaft, means for driving the conveyors of the binder from said conveyor shaft, and a vertical sickle operating shaft operatively connected to said drive shaft on the opposite side from which the sickle extends.

Des Moines, Iowa, December 24, 1925.

CORNELIUS P. HOUTSMA.
